US00D580292S

(12) **United States Design Patent**
Hamel

(10) **Patent No.:** **US D580,292 S**
(45) **Date of Patent:** **** Nov. 11, 2008**

(54) **DIAL**

(75) Inventor: **Anaïs Hamel**, Neuchâtel (CH)

(73) Assignee: **Montblanc-Simplo GmbH**, Hamburg
(DE)

(**) Term: **14 Years**

(21) Appl. No.: **29/320,158**

(22) Filed: **Jun. 23, 2008**

(30) **Foreign Application Priority Data**

Dec. 21, 2007 (CH) 134852

(51) **LOC (8) Cl.** **10-07**

(52) **U.S. Cl.** **D10/126**

(58) **Field of Classification Search** D10/30-39,
D10/123-126; 368/276, 281, 282, 285, 228,
368/232

See application file for complete search history.
